TIE LIFTER

Peter Ruggeri, Odell, Ill.

Application October 9, 1941, Serial No. 414,337

10 Claims. (Cl. 254—121)

In spiking rails to ties it is necessary that the tie be held up firmly against the rail. It is also highly desirable to hold the tie firmly against the rail when tamping ballast under the tie. Although various tie lifting devices have been proposed heretofore, none of them have been satisfactory for ordinary use, and as a result the construction or maintenance crews have had to rely on such awkward and labor-consuming practices as having one member of the crew pry up the end of the tie being spiked with a crowbar or the like while the spike was being driven. With two men usefully employed in driving the spikes on one end of the tie, the time of another would thus be wasted in holding up the tie.

According to the present invention, this loss of time and labor is avoided by the provision of a simple tie lifter which is capable of engaging the tie at its middle and drawing both ends tight against the rails at once while leaving all of the tie in the vicinity of the rails open and clear for the driving of the spikes. With a four-man crew, the tie can be raised into position with the structure of this invention and then all four men can drive the spikes—two at each end. The device is simple and light enough so that it is entirely practical to take it around with the crew.

Additional advantages and objects of the invention will be apparent from the following description and from the drawings, in which:

Fig. 1 is a longitudinal sectional view taken through one form of the invention chosen for illustration.

Fig. 2 is a plan view of the structure shown in Fig. 1.

Fig. 3 is a diagrammatic view illustrating the position of the tie lifter approximately midway between the rails, and illustrating also the fact that the tie is held tightly against both rails.

Fig. 4 is a transverse sectional view taken approximately on the line 4-4 of Fig. 1.

Fig. 5 is a plan view of the tongs taken approximately on the line 5-5 of Fig. 1.

Fig. 6 is a view corresponding to Fig. 1 but of a modified form of the invention designed to have a low enough clearance for trains to pass over it while it remains in position.

Two forms of the invention have been chosen for illustration and description, in compliance with section 4888 of the Revised Statutes.

In the form of the invention illustrated in Figs. 1 to 4, the standard 11 includes a pipe 12 bent to the shape clearly shown in Figs. 1 and 2, with a loop 13 forming a base or foot at one end, and a plate 14 secured to the ends of the pipe at the

other end to form a second base or foot. Of course, instead of the loop 13, a plate 14 could be provided at both ends, there then being two separate pipes instead of one pipe bent double.

5 The standard is of a length so that the two feet 13 and 14 will rest on first and third ties spaced in accordance with present railroad practice. An over-all length of 41 inches has been found satisfactory.

10 Positioned on the raised or bridge-forming portion of the standard generally midway of its length is a casting 16. As seen best in Fig. 2, the casting 16 has end portions 17, each of which straddles both legs of the pipe 12, and connecting webs 18 integral with the end portions 17. The casting 16 is clamped to the pipe 12 by nuts 19 on bolts 20, the nuts 19 bearing against cast blocks 21, each of which straddles the two portions of the pipe 12 as do the end portions 17 of the casting 16.

A pin 26 extends through the two webs 18, being held in place by any suitable manner as by cotter pins. Two plates 27 are pivotally carried by the pin 26, bearing loosely against the webs 18 and spaced apart by a lever 28 to which the two plates are preferably welded. In this manner it is seen that the plates form a drum on which a chain 29 may be wound, as clearly seen in Figs. 1 and 4, with alternate links 31 ex-

30 tending partially between the plates 27. This arrangement keeps the chain centered on the drum and at the same time provides relatively smooth chain actuation. The upper end of the chain is secured to the plates 27 by a pin 32 while the lower end of the chain is secured to tongs 34 as by means of an eye 36 riveted to a staple 37, which in turn is pivotally secured to the bifurcated ends 38 of the tong arm 39. The pivotal con-

40 nnection between staple 37 and arms 38 may comprise a pin riveted between the two sides of the staple or a screw 41 extending through one side and threaded into the other. One of the bifurcations 38 may be an integral portion of the arm 45 39 while the other is welded thereto as seen at 42 in Fig. 5.

The other tong member 43 is preferably matched as seen best at 44 in Fig 1, so as to permit the tongs to open out until the horizontal portions of the two arms 39 and 43 are substantially in alignment. As will be noted from Fig. 1, the opening out of the arms is also facilitated by positioning the screw 41 above the center line of arm 39. This construction is important in reducing the over-all height of the tongs and

this in turn is particularly important in connection with the structure shown in Fig. 6.

The lever 28 is long enough to give adequate leverage in operating the device. When it is operated in a counterclockwise direction, as seen in Fig. 1, it rotates the plates 27 about the pin or screw 41 to wind the chain 29 thereon, thus causing the teeth 46 to bite into the tie 47 and then raise the tie and hold it firmly against the rail 48. The teeth 46 may conveniently comprise plates welded to the arms 39 and 43, preferably two plates on each arm so as to give adequate bearing area for raising the tie without danger of excessively tearing the tie.

To hold the tie up, a ratchet 51 is provided, which is engaged by a pawl 52 carried by the lever 28. The pawl 52 operates smoothly and freely between the lever 28 and a guide casting 53 which may be secured rigidly to the lever by a rivet or by a nut and bolt 54 passing through a slot in the pawl 52. The pawl is spring pressed by a spring 55 bearing against a lug 56 formed on the casting 53 and projecting into a slot 57 formed in the pawl 52. The pawl 52 may be released by a handle 58 pivoted to the lever 28 and connected to the pawl 52 by a rod 59. The ratchet 51 is of course carried by the casting 16, as by one of the webs 18. In operating the device, the handle 58 is not squeezed and as a result the lever 28 is latched in any position to which it is moved, thus holding the tie 47 firmly against the rail. There is enough inherent resiliency in the parts and in the tie 47 so that the tie will be held resiliently in place and so that in spite of having fairly large teeth in the ratchet 51 it will always be easy to operate the lever 28 to a position where it latches and holds the tie firmly in place.

As seen in Fig. 3, the standard 11 is generally positioned approximately midway of the rails 48 so that it raises both ends of the tie against the rail simultaneously. Of course, by stating that the ends are raised against the rail, there is no intention of negating the conventional intervening tie plate 61, which for the purposes of this invention may be considered as part of the tie. This midway position of the standard 11 with all parts of the device remote from the rails makes the spikes with which the rail is secured to the ties fully accessible so that there is no interference with the swinging of the hammers with which the spikes are driven.

Frequently it is desirable to move the tie longitudinally of the tie a few inches before the spikes are driven in order to center the tie with respect to the rails. Ordinarily this involves a special operation with a crowbar or the like since the ties are too heavy to move very easily. With the present invention, however, it is merely necessary to either shift the standard 11 in the direction of desired movement, a distance equal to the distance of movement, or shift the tongs 34 in the opposite direction the same distance. This is of course done before the lever 28 is actuated to cause the tongs to bite into the tie, and hence either movement is accomplished with great ease. When the lever is actuated to raise the tie off of the bed on which it was resting, its own weight will swing it to a centered position with the tongs 34 directly below the standard 11.

The form of the invention shown in Fig. 6 is so devised that a train can pass over it while it is in place between the rails. To this end the standard 11 is made considerably lower than

the standard 11, and the ratchet 51, which in Fig. 1 extends a considerable distance above the standard 11, is omitted. In its place a ratchet 112 may be welded to the plates 113, and a pawl 114 may be secured to the standard as to one of the clamp blocks 121, the pawl 114 being drawn into engagement by a spring 123 and being released by a treadle 124. The dimensions of the standard 11, the plates 113 and the chain 129 are such that their maximum over-all height when they are resting on ties between the rails will be low enough for a train to pass over them. It is preferred that this maximum over-all height be not over 8½ inches in order that the device may be used safely with a 6-inch rail. Of course, 8¾ or 8 inches would be that much better, allowing for greater irregularities in the ties on which the device rests.

In order for a train to pass over the device, it is of course necessary that the lever 128 be in a lowered position. In order to permit the lever 128 to be kept in a lowered position even though the plates 113 are held in an actuated position by the pawl 114, a lost motion connection is provided between the lever 128 and the plates 113. This may conveniently be accomplished by mounting the lever 128 on the pin 126 independently of the plates 113 and providing a pin 131 extending through the plates 113 and projecting therefrom in the path of lever 128 so that when lever 128 is moved clockwise as seen in Fig. 6, it will strike the pin 131 and rotate the plates 113. The lever 128 may then be returned to its lower position shown in full lines in Fig. 6, while the pawl 114 holds the plates 113 in their actuated position, thus holding the tie firmly against the rail. To release the tongs from the tie, it is merely necessary to step on treadle 124 and release pawl 114. It will be understood, of course, that the webs 118 will be spaced apart a little farther than the webs 18 in order to provide room for the lever 128 and the ratchet 112 on the pin 126, between the webs 118.

It is in connection with the over-all height of the form shown in Fig. 6 that the illustrated construction of the tongs is important. It obviously must be possible for the tie to be raised to the rail without having the tongs strike any other part of the device. If the associated parts of the device are to be low in order for a train to pass over them, there is not much space between these associated parts and the raised position of the tie. By cutting out the notch 44 and by placing the pin 41 a little above the center line of arm 39, it is possible for the tongs to open until the generally horizontal portions of arms 39 and 43 are in alignment, so that in their starting position the tongs require only the spacing corresponding to the vertical width of the arms 39 and 43. Of course, with a small tie, the clamping movement of the tongs will require quite a little more space than this, but it is still less than if the tongs started their clamping movement from a point considerably above the tie.

It will be noted that in both Fig. 1 and Fig. 6 the pin 133, by which the two portions of the tongs are pivoted together, is displaced from the center. This serves the double purpose of evening the upward force on the two sides of the tie and of increasing the gripping force of the tongs 39, this force depending on the ratio of the distance from the pin 133 to the screw 41 and to the points of teeth 46 on arm 39.

Another feature found in both the forms of

Figs. 1 and 6 is the special shaping of the plates 27 or the eccentric mounting thereof. The advantage of this is that if the tie is spaced an unusual distance below the rail, it may be raised quickly by the part of the plates 27 having a large radius, although the smaller radius of the other portions of the plates will come into play as the tie reaches its final position. A smaller radius will of course enable the operator to exert more upward force on the tie with a given manual force applied to the lever 28.

From the foregoing it is seen that a very simple and dependable device is provided for holding a tie firmly against the rails at both ends thereof while spikes are being driven into the tie or while ballast is being tamped under the tie. The device is of such nature that it is fairly light and may be easily carried with the crew, and furthermore it leaves the portions of the tie in the vicinity of the rails fully accessible for driving the spikes or for tamping. One man can easily apply enough force to the operating lever to hold the tie against the rails with all the firmness that is required, and the latch will hold the tie there while the operator joins the rest of the crew in driving the spikes, if desired.

I claim:

1. A tie lifter including a humped standard adapted to rest at its opposite ends on ties generally midway between the two rails of a track, tongs extending parallel to the axis of the standard and adapted to engage a third tie between said ties, raising means carried by the hump of the standard for raising said tongs and said third tie therewith to draw it firmly against both rails including a grooved drum eccentrically pivoted to exert relatively more force at the end of its actuating stroke, and latch means for holding the raising means in its actuated position, all of said apparatus being substantially spaced from the portions of said third tie adjacent the rails whereby said portions are completely accessible for driving spikes therein.

2. A tie lifter including a humped standard adapted to rest at its opposite ends on ties generally midway between the two rails of a track, tongs extending parallel to the axis of the standard and adapted to engage a third tie between said ties, raising means carried by the hump of the standard for raising said tongs and said third tie therewith to draw it firmly against both rails, and latch means for holding the raising means in its actuated position, all of said apparatus being substantially spaced from the portions of said third tie adjacent the rails whereby said portions are completely accessible for driving spikes therein.

3. A tie lifter including a standard adapted to rest at its opposite ends on ties generally midway between the two rails of a track, tongs adapted to engage a third tie between said ties, raising means carried by the standard for raising said tongs and said third tie therewith to draw it firmly against both rails, and latch means for holding the raising means in its actuated position, all of said apparatus being substantially spaced from the portions of said third tie adjacent the rails whereby said portions are completely accessible for driving spikes therein.

4. A tie lifter including a standard adapted to rest at its opposite ends on ties generally midway between the two rails of a track, tongs adapted to engage a third tie between said ties, raising means carried by the standard for raising said tongs and said third tie therewith to

draw it firmly against both rails, all of said apparatus being substantially spaced from the portions of said third tie adjacent the rails whereby said portions are completely accessible for driving spikes therein.

5. A tie lifter including a standard longer than the width of a tie adapted to rest at its opposite ends on ties of a track, tongs adapted to engage a third tie which is approximately parallel with and between said ties, raising means carried by the standard for raising said tongs and said third tie therewith to draw it firmly against both rails, and latch means for holding the raising means in its actuated position.

6. Tie-lifting apparatus including means for engaging a tie adapted to lift the same, connecting means connected thereto, a standard adapted to be supported in a substantially fixed position with respect to the rails associated with the tie and with all parts thereof remote from the portions of the tie adjacent the rails whereby said portions will be fully accessible for driving spikes therein, and manually operable means carried by the standard for raising the tie-engaging means and the tie to draw the tie firmly against the rail including pivotally mounted drum means onto which the connecting means is wound, a handle pivotally mounted coaxially with the drum means and arranged to rotate the drum when actuated in one direction and to be free to move independently of the drum means in the other direction, and means to retain the drum means in its actuated position.

7. Tie-lifting apparatus including means for engaging a tie adapted to lift the same, connecting means connected thereto, a standard adapted, while the tie is engaged by said tie engaging means, to be supported in a substantially fixed position with respect to the rails associated with the tie and with all parts thereof remote from the portions of the tie adjacent the rails whereby said portions will be fully accessible for driving spikes therein, and manually operable means carried by the standard for raising the tie-engaging means and the tie to draw the tie firmly against the rail including pivotally mounted drum means onto which the connecting means is wound, said drum means being eccentrically pivoted so that a given force applied thereto will exert a greater raising force as the tie comes into engagement with the rail than when it is remote from the rail.

8. Tie-lifting means including tie-engaging means, a chain connected thereto, a portable standard adapted to rest on horizontal surfaces, a pair of plates supported by and pivotable with respect to the standard and spaced apart a distance appropriate for receiving one side of alternate links of the chain while the intervening links rest on the edges of the plate, and means for pivoting said plates and winding the chain thereon to raise the tie-engaging means without causing the tie to swing due to twisting of the chain.

9. Tie-lifting apparatus including means for engaging a tie adapted to lift the same, connecting means connected thereto, a standard adapted to be supported on the rail-bed and with all parts thereof remote from the portions of the tie adjacent the rails associated therewith whereby said portions will be fully accessible for driving spikes therein, and manually operable means carried by the standard for raising the tie-engaging means and the tie to draw the tie firmly against the rail including pivotally mounted drum means onto which the connecting means is

wound, a handle pivotally mounted coaxially with the drum means and arranged to rotate the drum when actuated in one direction and to be free to move independently of the drum means in the other direction, and means to retain the drum means in its actuated position; said handle being movable to a position where it is substantially as low as the top of the drum and all parts of said apparatus being sufficiently low to permit a train to pass over said apparatus when the apparatus is resting on the rail-bed.

10. Tie-lifting apparatus including a standard forming a bridge adapted to be disposed transversely over the intermediate portion of a tie and to be supported at opposite sides of the tie and

5
10
15

having a raised span above its ends and above the tie, tie-engaging means adapted to lift a tie in a manner to lift both ends of the tie simultaneously while the standard is disposed remotely from the portions of the tie adjacent to the rails positioned thereabove to be spiked thereto whereby said portions will be fully accessible for driving spikes therein, and manually operable means carried by the raised span of the standard for raising the tie-engaging means and the tie to draw the tie firmly against the rails, said manually operable means being adapted to be mechanically maintained in its actuated position until manually released.

PETER RUGGERI.
